UNITED STATES PATENT OFFICE

131,531

DESIGN FOR A PIN OR SIMILAR ARTICLE

Florence Nathan, New York, N. Y., assignor to Eisenberg Jewelry, Inc., Chicago, Ill., a corporation of Illinois

Application January 10, 1942, Serial No. 105,110

Term of patent 3½ years

To all whom it may concern:

Be it known that I, Florence Nathan, a citizen of the United States, residing at New York, in the county of New York and State of New York, have invented a new, original, and ornamental Design for a Pin or Similar Article, of which the following is a specification, reference being had to the accompanying drawing, forming a part thereof.

In the drawing:

Fig. 1 is a face view of the pin or similar article, showing my new design; and

Fig. 2 is an edge view of the pin or similar article.

I claim:

The ornamental design for a pin or similar article, substantially as shown.

FLORENCE NATHAN.
